UNITED STATES PATENT OFFICE

104,608

DESIGN FOR A PASTRY BLENDER

Carrie M. Bricker, Cleveland, Ohio

Application March 29, 1937, Serial No. 68,463

Term of patent 14 years

To all whom it may concern:

Be it known that I, Carrie M. Bricker, a citizen of the United States, residing at Cleveland, in the county of Cuyahoga and State of Ohio, have invented a new, original, and ornamental Design for a Pastry Blender, of which the following is a specification, reference being had to the accompanying drawing, forming part thereof.

In the drawing:

Fig. 1 is a front elevation of a pastry blender, showing my new design;

Fig. 2 is an end elevation thereof; and

Fig. 3 is an inverted plan view thereof.

I claim:

The ornamental design for a pastry blender, as shown.

CARRIE M. BRICKER.
